UNITED STATES PATENT OFFICE.

HUGO JOHN, OF ILVERSGEHOFEN, NEAR ERFURT, GERMANY, ASSIGNOR TO THE SCHORNSTEIN-AUFSATZ UND BLECHWAREN-FABRIK J. A. JOHN AKTIEN-GESELLSCHAFT, OF ILVERSGEHOFEN, NEAR ERFURT, GERMANY.

STEAM WASHING-MACHINE.

No. 834,382.

Specification of Letters Patent.

Patented Oct. 30, 1906.

Application filed October 28, 1903. Serial No. 178,829.

To all whom it may concern:

Be it known that I, HUGO JOHN, a subject of the German Emperor, and a resident of Ilversgehofen, near Erfurt, Germany, have 5 invented an Improved Steam Washing-Machine, of which the following is a specification.

The annexed drawings, given by way of example, show a species of a washing-machine 10 of this description which takes up a very little space indeed and which can be used as a kitchen-stove.

Figure 1 shows a side view of the machine. Fig. 2 is a central vertical section thereof. 15 Fig. 3 is a vertical section taken in a plane at ninety degrees to that of Fig. 2. Fig. 4 is a horizontal section on A B of Fig. 3, showing the stove's interior with grate. Fig. 5 is a horizontal plan view of the washing-machine 20 with the cover taken off. Fig. 6 is a sectional detail of an improved form of bearing, showing the journal of the washing-drum seated therein; and Fig. 7 is an end view thereof. Fig. 8 shows an elevation of the 25 washing-machine and heating device belonging thereto packed up.

The heating device 1 of the washing-machine is supported upon four inclined legs 3, between which when the washing-machine is 30 packed up are placed the recipient 2 and cover 4. The cinder-box 5 fits freely into the fireplaces 8 with the fire-pot 6 and grill 7 and is placed therein when the machine is packed up, Figs. 1, 2, 8. The plate 9 above 35 the fireplace 8 is provided with an opening 10, through which the base 11 projects, the latter extending into said fireplace. The bottom 14 of the recipient 2 bears upon the plate 9, so that it is heated upon the largest possible 40 surface and can at all times be easily lifted off from the fire.

To prevent the combustion-gases from immediately escaping through the chimney, a fire-bridge 16 is arranged upon the side of the 45 stove 6 immediately in front of the chimney 15. This bridge by retarding the products of combustion permits a more complete utilization of the heat units thereof.

The grill 7 is arranged inside the fire-pot,

so as to be easily withdrawn therefrom. 50 Grills of different openings may be used for the purpose of using the heating device for all combustibles.

The hollow spindle 17 of the washing-drum 12 is placed in two lugs 18, bent in a half-circle, the upper ends whereof are connected to the lateral lugs 19, which partially surround with their lower ends 20 the edge of the recipient 2, to which they are fixed by means of lug 21. The lateral lugs 19 are 60 made in a single piece with their fixture-lugs 21, Figs. 6 and 7. By this arrangement the fixture of the washing-drum is rendered very lasting and solid. The friction is decreased to the utmost degree. 65

If it be desired to utilize the heating device 1 of the washing-machine as a kitchen-stove, the recipient 2, with the drum 12 and cover 4, is lifted off the plate 9, and the opening 10 is closed in the usual manner by means of 70 rings fitting one into the other.

The washing-machine just described and which can be heated by any means can therefore be used as kitchen-stove by taking off the washing device, while completely utilizing the gases of combustion. By reason of its construction it can be packed into the 75 smallest possible space.

Having now fully described my invention, what I claim, and desire to secure by Letters 80 Patent, is—

In an apparatus of the character herein set forth the combination of a heating device provided with legs; a removable recipient mounted upon said heating device, said recipient being made substantially in the form of an inverted truncated pyramid, and having a similarly-shaped cover thereon; a washing-drum mounted in said recipient, said recipient adapted to fit closely between said 85 legs to effect the saving of space when the parts of the device are packed for shipping, substantially as described. 90

HUGO JOHN.

In presence of—

J. E. WILLIAMS,
O. JOHN.
